ATTORNEYS

UNITED STATES PATENT OFFICE.

HENRY CLAYTON BARNES, OF SWANTON, VERMONT.

BARREL-COVER.

SPECIFICATION forming part of Letters Patent No. 289,206, dated November 27, 1883.

Application filed October 24, 1883. (No model.)

To all whom it may concern:

Be it known that I, H. C. BARNES, a citizen of the United States, residing at Swanton, in the county of Franklin and State of Vermont, 5 have invented certain new and useful Improvements in Barrel-Covers; and I do declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 of the drawings is a representation 15 of this invention applied to a barrel, and is a perspective view. Fig. 2 is also a perspective view, and shows the cover by itself. Fig. 3 is a detail in section, to show the backward slant of the kerf.

20 The invention has relation to barrel-covers; and it consists in the construction and novel arrangement of devices, as will be hereinafter fully described, and particularly pointed out in the claim appended.

25 Referring by letter to the accompanying drawings, *a* designates the barrel, the upper head of which is removed. The cover is made in two sections, *b c*, hinged together. The section *b* is provided on its under face with blocks 30 *d d*, which abut against the inner periphery of the barrel when in place. The rim or edge *f* of the section *b* is recessed at *g g*, to form

seats for the upper extensions of the angular hook-arms *h h*. At one end of each recess an under inclined kerf, *i*, is made, to receive the 35 arm *h* and permit it to be fastened at its lower end to the barrel, or to permit it to be turned under when the covers are to be packed for transportation. The upper extensions, *k*, are secured in place by staples *l l*. 40

This cover can be applied to the barrel by placing it in position and driving the hook-ends of the arms into the barrel, and it can be as readily removed by withdrawing the 45 hooks. A suitable latch or fastening may be provided for the larger section of the cover to hold it closed, if desired.

Having thus fully described my invention, what I claim as new, and desire to secure by 50 Letters Patent, is—

As an improved article of manufacture, a sectional barrel - cover having its sections hinged together, and the smaller-section provided with abutment-blocks on its under face, in combination with hinged hook-arms seated 55 in recesses in the rim of the rear section, and adapted to engage the body of the barrel by their hook ends, substantially as specified.

In testimony whereof I affix my signature in presence of two witnesses.

HENRY CLAYTON BARNES.
